United States Patent Office

Des. 197,162
Patented Dec. 17, 1963

197,162

AUTOCLAVE

Fred K. Storm, 1425 Allen Ave., Glendale, Calif.

Filed Apr. 22, 1963, Ser. No. 74,565

Term of patent 14 years

(Cl. D83—12)

FIG. 1.

FIG. 2.

FIG. 3.

FIG. 4.

FIG. 5.

FIG. 1 is a side elevational view of an autoclave showing my new design;

FIG. 2 is a front view of the autoclave shown in FIG. 1;

FIG. 3 is a top view thereof;

FIG. 4 is a back view thereof; and

FIG. 5 is a perspective view of the autoclave shown in FIG. 1.

I claim:

The ornamental design for an autoclave, as shown.
